(57) **CLAIM**

I claim the ornamental design for an outsole for a shoe, as shown and described.

DESCRIPTION

FIG. 1 is a bottom perspective view of an outsole for a shoe showing my new design;

FIG. 2 is a bottom view thereof;

FIG. 3 is a left view thereof;

FIG. 4 is a right view thereof;

FIG. 5 is a front view thereof; and,

FIG. 6 is a rear view thereof.

The broken line showing an oval shape in the arch area of FIGS. 1 & 2, along with the parallel broken lines around the peripheries of FIGS. 1, & 3–6, represent the boundaries of the design; with the neither the lines themselves nor the areas within them forming any part of the claim.
